COMBINED LETTER OPENER, WRITING INSTRUMENT AND PENCIL SHARPENER

Frank W. Derenski, 11009 Morrison St.,
Los Angeles, Calif.

Filed Jan. 18, 1965, Ser. No. 83,472

Term of patent 14 years

(Cl. D74—17)

I claim:

The ornamental design for a combined letter opener, writing instrument and pencil sharpener, as shown.
